DOOR CHECK

Frederick W. Beyer, Detroit, Mich., assignor to
 National Stamping Company, a corporation of
 Michigan

Application January 22, 1949, Serial No. 72,109

8 Claims. (Cl. 16—86)

1

This invention relates to a device for checking the opening movement of a hinged door and for releasably retaining the door in an open position.

It is an object of this invention to provide a door check which includes means for releasably retaining a hinged door in an open position, as well as means for checking the opening movement of the door.

It is a further object of this invention to provide a door check of the aforementioned type which includes an arm or link which has one end thereof connected to the hinged door and the opposite end thereof projecting through an aperture in a retainer member, connected to a door supporting pillar, and which carries a single leaf spring member and a cushioning element for engaging the retainer member so as to check the opening movement of the door and releasably retain the door in an open position.

It is a further object of this invention to provide a door check of the aforementioned type in which the leaf spring frictionally and slidably engages the retainer member at all times so that there will be no play or rattling between the door check parts irrespective of the position of the hinged door with respect to the pillar and striker plate.

It is a further object of this invention to provide a door check device of the aforementioned type in which a cushioning element is supported on the inner end of the arm for limiting the maximum extent to which the hinged door may be opened.

It is a further object of this invention to provide in a door check of the aforementioned type, a rigid member on the arm, adjacent to the cushioning element, which movably positions one end of the leaf spring on the arm, thereby eliminating the necessity of any special fastening devices for connecting the leaf spring end to the arm.

It is a still further object of this invention to provide, in a door check device of the aforementioned type, an arm which is channel shaped in cross section, so as to be especially strong and rugged in construction, even though formed from relatively light sheet metal, and so as to provide a longitudinal guideway in which the leaf spring is positioned.

It is a still further object of this invention to provide a door check device of the aforementioned type which is relatively economical to manufacture, simple in construction and efficient in operation.

It is a still further object of this invention to provide, in a door check device of the aforemen-

2

tioned type, a novel striker or retainer plate which is simple in construction, efficient in operation and exceptionally durable.

These and other objects of this invention will become apparent from the following detailed description, taken in conjunction with the accompanying drawings, in which:

Fig. 1 is a fragmentary horizontal sectional view through a swinging door, supporting hinge pillar therefor, and a door check device of this invention, showing the arrangement of the parts when the door is in its open position;

Fig. 2 is a horizontal sectional view, similar to Fig. 1, showing the arrangement of the parts when the door is in its closed position;

Fig. 3 is a sectional view of the structure illustrated in Fig. 2, taken along the line 3—3 thereof;

Fig. 4 is an exploded perspective view of the door check arm and leaf spring carried thereby;

Fig. 5 is a fragmentary end elevational view of the structure illustrated in Fig. 1, taken in the direction of the arrow 5 thereon;

Fig. 6 is an enlarged sectional view of the structure illustrated in Fig. 1, taken along the line 6—6 thereof;

Fig. 7 is a sectional view of the structure illustrated in Fig. 1, taken along the line 7—7 thereof;

Fig. 8 is a horizontal sectional view similar to Fig. 1, and illustrating a further embodiment of the invention;

Fig. 9 is a sectional view of the structure illustrated in Fig. 8, taken along the line 9—9 thereof;

Fig. 10 is an enlarged end elevational view of the retainer or striker plate illustrated in Fig. 8; and

Fig. 11 is an enlarged sectional view of the structure illustrated in Fig. 10, taken along the line 11—11 thereof.

It will be appreciated that in the broad aspects of this invention the door check arm may be connected to any suitable part of a door member or its adjacent supporting member, and the retainer means may be connected to or form a part of either of such members. For example, the retainer means may be formed in one of the butt plates of a door hinge and the arm connected to the other butt plate of the hinge. However, in the more limited aspects of the invention, as shown in the drawings, and more particularly in Figs. 1—7, wherein a preferred embodiment of the invention is illustrated, it will be seen that the door check device includes a rigid elongated arm 13 which has one end thereof pivotally connected to a vehicle door member 15 by means of a pivot pin or rivet 17 and bracket 18. The

opposite end of the arm 13 extends through an opening 19 in the outer wall of a vehicle body supporting member or pillar 21. The vehicle door member 15 is hingedly connected to the pillar 21 at 23, in a conventional manner. A retainer member 25 is secured to the inner face of the outer wall of the pillar 21, behind the opening 19 therein, and includes a bracket 26 having a retainer or keeper plate 27 secured to the inner face thereof. The bracket 26 is provided with an opening 28 and the plate 27 is provided with an elongated opening 29 in which the arm 13 is movably positioned and supported. An enlarged substantially flat head portion 31 is formed on the inner end of the arm 13, and is disposed inwardly of the retaining plate 27 when the door check is installed on a vehicle as shown.

A rigid washer-like member 33, having an elongated central aperture 35, is sleeved on the arm 13 and abuts the enlarged arm head portion 31. A cushioning element 37, which has an elongated central aperture 39, is sleeved on the arm 13 and abuts the rigid member 33. The cushioning element 37 engages the inner face of the retaining plate 27 when the vehicle door 15 is in its fully opened position, as illustrated in Fig. 1, so as to limit the maximum extent of opening movement of the door.

The arm 13 is, as can be best seen in Fig. 7, channel shaped in cross section; that is the opposite longitudinal sides of the arm 13 are bent upwardly at 41. The channel shaped arm construction permits the arm to be formed from relatively light gauge metal. An elongated leaf spring strip 43 is positioned in the channel portion of the arm 13, that is, the spring strip 43 is positioned on the upper face of the arm 13 between the upwardly bent sides 41 thereof. The spring strip 43 is downwardly offset at its outer end, as indicated at 45, so that the offset portion abuts the upper face of the arm 13 adjacent the extreme outer end thereof. The opposite or inner end of the spring strip 43 extends through the cushioning element central opening 39, and the rigid washer member central opening 35, so as to be movably positioned and guided thereby. Therefore, the portion of the spring strip between the rigid washer-like member 33, on the inner end of the arm 13, and the offset portion 45, adjacent the outer end of the arm 13, is spaced above the upper face of the arm so as to be compressible toward the arm upper face. Due to the fact that the inner end of the spring strip 43 is movable longitudinally of the washer-like member 33, such compression is possible. The spring offset portion 45 is provided, adjacent its outer end, with an aperture 47, and the rivet or pivot pin 17 which connects the arm 13 to the door bracket 18 also connects the outer end of the spring strip 43 to the arm 13. However, when the door check device is sent to an automobile manufacturer for installation, the outer end of the spring strip 43 need not be connected to the arm, as the spring strip will normally be retained on the arm by the frictional engagement of its inner end with the cushioning element 37 and the rigid washer member 33.

The spring strip 43 is provided adjacent the arm cushioning element 37, with a plurality of longitudinally spaced, outwardly bowed portions 49, which are adapted to engage a wall of the retainer plate opening 29 so as to aid in checking the opening movement of the door and so as to releasably retain the door in an open position. When the door is opened outwardly

bowed portions 49 engage a wall of the retainer plate opening 29 and the spring strip is compressed toward the arm so as to permit the bowed portions to pass through the retainer plate opening and releasably retain the door in its open position. As there are a plurality of bowed portions the door can be releasably retained in either its fully open position or in partially opened positions. By offsetting the spring strip 43 adjacent its outer end, it will be appreciated that the intermediate portion of the spring strip will resiliently maintain the arm and strip in frictional engagement with the walls of the retainer plate opening 29 so that there will be no play between the arm 13 and the retainer plate 27, which would cause any rattling when the device is installed on a vehicle.

Thus, the door check device of this invention is constructed so that only a single leaf spring strip is employed and the spring strip has its inner end movably positioned and guided by the rigid washer-like member 33, so that no additional attaching means need be provided for securing the end of the spring strip to the arm. By extending the end of the spring strip through the washer member 33, the outer end of the spring strip is prevented from moving laterally with respect to the arm but the spring strip can, when compressed, move longitudinally with respect to the washer member 33. Furthermore, with the construction of this invention, the annoyance of having the door check device rattle when installed in a vehicle, is completely eliminated by the resilient and frictional engagement of the spring strip and arm with the retaining plate opening walls, even when the door is completely closed as illustrated in Fig. 2.

Referring now to the embodiment illustrated in Figs. 8 through 11, it will be seen that the arrangement of the parts is the same as that previously described. In this embodiment, the door check arm 13' is not channel shaped, as in the previous embodiment, but is made out of a heavier gauge metal, so that no reinforcing upturned flanges are necessary. Also, in this embodiment, the retaining member 25' is different in construction than the member illustrated in the previous embodiment. In this embodiment, the inner wall of the retainer bracket 26' has a plate 51 secured to its outer face and a plate 53 secured to its inner face. The bracket 26' has an elongated central aperture 28', as previously described, and the outer plate 51 has a tablike projecting portion over the aperture 28', reversely bent, as indicated at 55, around one side wall of the aperture 28', so as to reinforce the same. The inner plate 53, similarly, has a tablike projecting portion which is reversely bent at 57, in the opposite direction, so as to reinforce the opposite edge of the bracket aperture 28'. With this construction there is no need for a retainer plate, such as plate 27 in the previous embodiment, and the retainer member 25' is exceptionally strong and durable and the danger of the wall, which defines the opening 28', breaking away or becoming damaged is materially lessened by the reinforcing tab portions of the inner and outer retainer plates 51 and 53.

Except for the above enumerated differences between the embodiment illustrated in Figs. 8 through 11 and the embodiment illustrated in Figs. 1-7, the door check devices are identical in construction and in function, so that a further description of the function of the door check device illustrated in Figs. 8 through 11 is not

deemed necessary and like parts in the latter embodiment are designated by primed numbers corresponding to like numbers in the first embodiment.

What is claimed is:

1. A device for releasably retaining in an open position a door member hingedly supported on a supporting member, including a rigid arm having one end thereof adapted to be connected to one of said members, retaining means connected to the other of said members, including a plate-like element having an aperture therein for the reception of said arm, a rigid member sleeved on said arm, abutment means on said arm adjacent one end thereof against which said rigid member is positioned, a cushioning element sleeved on said arm and abutting said rigid member, a leaf spring member positioned on said arm and having one end thereof extending through said cushioning element and rigid member while the opposite end thereof is adapted to be connected to said arm, said spring being compressible against said arm by the edges of said retaining means plate aperture, so as to aid in checking the opening movement of the door and releasably retain the latter in an open position.

2. A device for releasably retaining in an open position a door member hingedly supported on a supporting member, including a rigid arm having one end thereof adapted to be connected to one of said members and having an abutment adjacent the opposite end thereof, a striker plate having an aperture therein for the reception of said arm, a rigid member sleeved on said arm and engaging said arm abutment, a cushioning element sleeved on said arm and abutting said rigid member, a leaf spring positioned on said arm frictionally engageable with an edge of the striker plate aperture and having one end thereof extending through said cushioning element and rigid member while the opposite end thereof is adapted to be connected to said arm, an offset portion on said spring adjacent to but spaced longitudinally of said cushioning element which is adapted to be engaged by and move past an edge of said striker plate aperture so as to compress said spring against said arm and aid in checking the opening movement of the door as well as releasably retaining the latter in an open position.

3. A device for releasably retaining in an open position a door member hingedly supported on a supporting member, including a rigid elongated arm which is channel shaped in cross section and one end of which is adapted to be connected to one of said members, an abutment on the other end of said arm, a striker plate connected to the other of said members and having an opening therein for the reception of said arm, a rigid member sleeved on said arm and engaging said arm abutment, a cushioning element sleeved on said arm and having one face thereof abutting said rigid member and the opposite end thereof adapted to abut one face of said striker plate, a leaf spring member positioned in said arm channel and having one end thereof extending through and movably positioned by said cushioning element and rigid member, while the opposite end of said spring member is adapted to be connected to said arm, said spring being compressible against said arm by the edges of said striker plate opening so as to aid in checking the opening movement of the door and releasably retain the latter in an open position.

4. A device for releasably retaining in an open position a door member hingedly supported on a supporting member, including a rigid elongated arm having one end adapted to be connected to one of said members, an abutment on the opposite end of said arm, a striker plate having an opening therein for the sliding reception of said arm, a rigid member sleeved on said arm and engaging said arm abutment, a cushioning element sleeved on said arm and having one face thereof abutting said rigid member and the opposite face thereof adapted to abut said striker plate adjacent said striker plate opening, a leaf spring member positioned on one face of said arm and having one end thereof extending through said cushioning element and rigid member and engageable by an edge of said striker plate opening, an inwardly offset portion adjacent the opposite end of said leaf spring engaging said face of said arm adjacent the end where it is adapted to be connected to one of said members, whereby the portion of said spring between said rigid member and the offset end opposite thereof will be spaced from the face of said arm so that said spring will frictionally engage an edge of said striker plate opening throughout its entire movement in the striker plate opening, when the latter are connected in a door structure, so as to aid in checking the opening movement of the door and releasably retain the latter in an open position.

5. A door check structure including an elongated rigid arm, an abutment on one end of said arm, a rigid member sleeved on said arm and engaging said arm abutment, a cushioning element positioned on said arm and abutting said rigid member, a leaf spring member positioned on said arm and having one end thereof extending through said cushioning element and rigid member, while the opposite end thereof is adapted to be connected to said arm, a plurality of longitudinally spaced outwardly bowed portions on said spring adapted to be compressed against said arm.

6. A door check structure including a rigid elongated arm which is channel shaped in cross section, an abutment on one end of said arm, a rigid member sleeved on said arm and engaging said arm abutment, a cushioning element sleeved on said arm and abutting said rigid member, a leaf spring member positioned in said arm channel and having one end thereof extending through and movably positioned by said cushioning element and rigid member, while the opposite end thereof is adapted to be connected to said arm, a plurality of longitudinally spaced outwardly bowed portions on said spring member adjacent said cushioning element adapted to be compressed against said arm.

7. A door check structure including a rigid elongated arm, an abutment on one end of said arm, a rigid member on said arm engaging said arm abutment, a cushioning element on said arm abutting said rigid member, a leaf spring member positioned on one face of said arm and having one end thereof extending through said cushioning element and rigid member, an inwardly offset portion at the opposite end of said leaf spring engaging said arm face adjacent one end thereof, whereby the portion of said spring between said rigid member and said offset end will be spaced from the face of said arm and will be compressible towards said arm.

8. A door check structure including a plate having an aperture therein, a pair of plates se-

cured to the opposite faces of said first plate, an integral projecting portion of one of said plates above said first plate aperture being reversely bent around one edge of said first plate aperture, an integral projecting portion of said second plate adjacent said aperture being reversely bent in the opposite direction over the opposite edge of said first plate aperture.
